United States Patent Office

Des. 199,090
Patented Sept. 8, 1964

199,090

CONTAINER FOR VOLATILE LIQUID OR THE LIKE

Alfonso M. Donofrio, Toledo, Ohio, assignor to Palmer
Pann Corporation, Toledo, Ohio, a corporation of Ohio

Filed Feb. 17, 1961, Ser. No. 63,968

Term of patent 14 years

(Cl. D58—25)

FIG. 1 is a front elevational view of a container for a volatile liquid or the like showing my new design;
FIG. 2 is a side elevational view thereof;

FIG. 3 is a top perspective view thereof, on a reduced scale;

FIG. 4 is a bottom plan view thereof;

FIG. 5 is a top plan view thereof; and

FIG. 6 is a bottom perspective view thereof on a reduced scale.

I claim:

The ornamental design for a container for volatile liquid or the like, as shown.
